UNITED STATES PATENT OFFICE

95,292

DESIGN FOR A CASING FOR AN AUTOMOBILE SIGNAL LIGHT

Harold O. Smith, Philadelphia, Pa.

Application January 8, 1934, Serial No. 50,351

Term of patent 14 years

To all whom it may concern:

Be it known that I, Harold O. Smith, a citizen of the United States of America, residing in the city of Philadelphia, county of Philadelphia, State of Pennsylvania, have invented a new, original, and ornamental Design for a Casing for Automobile Signal Lights, of which the following is a specification, reference being had to the accompanying drawing, forming part thereof.

In the drawing:

Figure 1 is a top plan view of the casing.

Figure 2 is a front view.

Figure 3 is a side view of the same.

I claim:

The ornamental design for a casing for an automobile signal light as shown.

Signed by me at Baltimore, Maryland, this 22 day of December, 1933.

HAROLD O. SMITH.
